AUTOMATICALLY EXPANDIBLE POLISHING
AND BUFFING WHEEL

Hiram J. Barton and Robert H. Barton, Detroit,
Mich., assignors of thirty-one one-hundredths
to Frank L. Szafranski and one-tenth to
Charles E. Wisner, both of Detroit, Mich.

Application January 2, 1940, Serial No. 312,044

17 Claims. (Cl. 51—190)

This invention relates to buffing and polishing wheels utilized in the final finishing of surfaces of metal, wood or other material and the object of the invention is to provide an automatically expandable wheel of such character of construction that the wheel is expanded by rotation of the wheel in the polishing operation.

More specifically the invention is involved in a wheel having a series of elements or shoes that are radially movable and arranged in a circle in which each shoe forms a part. Each of the shoes has a plate attached thereto and the plates arranged in a tongue and groove relationship with the contiguous segments. An endless buffing or polishing belt is mounted on the segments and is of such character as to stretch and thus permit the radially movable elements to move outwardly. An endless coiled spring is utilized to move the radially movable shoes inwardly, the wheel having a peripheral groove to receive the said shoes and a cam ring having a series of cams therein for radially moving the said shoes by rotation of the wheel in respect to the said shoes.

It is therefore a principal object of the invention to provide a wheel having a peripheral channel in its face in which channel the said shoes may move radially and peripherally and a belt carrying a polishing or abrading surface supported by the shoes and plates providing a construction whereby, in bringing the belt face in contact with a surface to be polished or buffed, the resistance of the belt to rotation produced by the contact thereof with the work tends to hold the belt from rotation thereby causing the cams to act to expand the belt and, the greater the pressure of the belt on the work, the greater will be the expansion of the band there being means provided to limit the extent to which the band may be expanded as hereinafter described.

These and various other features and objects of the invention are attained by the wheel shown in the preferred form in the accompanying drawings in which—

Fig. 1 is a side elevation of the wheel.

Fig. 2 is a section of wheel taken on line 2—2 of Fig. 1 with parts broken away to more clearly show structural features.

Fig. 3 is a section taken on line 3—3 of Fig. 1.

Fig. 4 is an enlarged face view of a shoe utilized in supporting the belt.

Fig. 5 is a side elevation of the shoe shown in Fig. 4.

Fig. 6 discloses a fragmentary cross section of a modified form of the polishing rim.

It is firstly to be understood that the wheel may be used for various purposes in buffing or polishing metal surfaces as, for instance, the exterior surface of a metal automobile body portion, an automobile engine crank shaft at the bearing points and points of connection of the connecting rod or any other character of objects formed of wood or other non-metallic material required to be polished or buffed by means of a wheel.

In its preferred construction, the wheel consists of a body 1 formed of two parts secured together and having a central hub 2 for mounting on a shaft. The rim 3 is formed to provide a peripheral channel 4 which at its outer periphery has an inturned edge or flange 5 on each side providing a central peripheral opening to receive a metal shoe 6. On the periphery of each shoe is a metal plate 7 and the several plates form a circle and support the belt. The shoes are of a generally U-shape and thus the assembled shoes provide a channel 8 in the inner peripheral surface and the outer face of each of these shoes is likewise provided with a groove 9 which together form a channel in which is mounted an endless coiled spring 10 tending to move the several shoes inwardly in the channel 4 of the wheel. The shoe plate 7 secured to each of the radially movable shoes 6 is notched at one end as at 9a and 10a providing tongues 11, 12 and 13 and at the opposite end of each shoe plate 7 has outwardly extending tongues 14 and 15 which fit in the spaces 9a and 10a of the next succeeding shoe plate and the assembled shoes and plates provide a foundation for the polishing or abrading belt 16.

The belt is to be understood as being of endless form having a latex or rubber-like base formed of any desirable material in the outer face of which the polishing or buffing elements 17 are secured. This surface of the polishing belt 16 may be provided with any desired character of a buffing or polishing material as, for instance, a wool-like surface consisting of fibrous material of various characters depending upon the particular work required to be performed by the wheel or it may have an abrasive surface indicated at 18 in Fig. 6. This surface may be formed by abrasive particles of any desired fineness and character embedded in a rubber-like or composition base 19 as may be required by the material to be surfaced.

The wheel is therefore adapted for use with various characters of polishing or abrading or buffing belts and the invention is not limited

to the specific character of belt used except that the belt should be limitly elastic and preferably within the range of three to five percent of its diameter by the shoes moving outwardly from a contracted position in which the belt may be slipped over the shoe plates when one or the other of the retaining rings 20 or 21 is removed and in the expansion, which is produced as hereinafter more fully described, the shoes in moving outwardly provide such frictional contact between the belt and the shoe plates as to prevent a relative rotation thereof.

Each of the shoes, as will be understood from Fig. 3, is formed with an outer portion 22 of less width than the body of the shoe thus providing a shoulder 23 which engages the inturned edges 5 of the wheel rim when the shoes are expanded to full extent. It will be noted that the plates 7 of each shoe, when in contracted position shown in Fig. 3, engage the outer face of the flanged ends 5 of the wheel rim and, to prevent lateral displacement of the belt 16, the retaining rings 20 and 21 extend outwardly on opposite sides of the belt to such distance that the outer peripheral edges of the rings 20 and 21 engage the side faces of the base of the band when the band is fully expanded.

The shoes and band are expanded by a cam ring indicated at 24 which is secured between the two half parts of the wheel as by the screws 25 of which there are a number as indicated in Figs. 2 and 3. The two half parts of the wheel, in the structure here shown, are secured together by bolts 26. The cam ring 24 has a series of cams 27 there being one cam for each shoe and the shoes are held in equi-spaced relation in either the expanded or contracted position by means of pins 28 carried in the flanges of each shoe and the flanges of each shoe have a recess 29 of similar form in its outer side face into which a small diameter end 30 of the pins project. These recesses 29 are formed at the outer edge on a radius and in these spaces 29 are positioned what we have termed spacer rings 31 and 32 to the shoes which rings have radial slots 33 into which the small diameter ends 30 of the pins extend.

The shoes are therefore all maintained in equi-spaced relation by the rings and the slots permit the shoes to be moved outwardly by the respective cams 27 or inwardly by the spring 10. The pins are therefore held in engagement with the respective cams by the spring and as the shoes ride freely in a radial direction in the recess 4 by rotation of the wheel when the band 16 is in contact with the work, the pins ride up on the cam and expand the belt and the expansion is limited by the shoulders 23 of the shoes engaging the inner face of the flanges 5 of the wheel rim.

The shoe plates 7 provide a continuous foundation for the belt even in the fully expanded position due to the inter-engaging notches 9 and 10 of one shoe plate with the projecting portions of the next succeeding shoe plate of the series. Thus while in the expanded position the shoes will be spaced a greater distance apart than in the contracted position, the tongues and notches of the plate 7 span such space and support the belt or band 16.

Under this relationship of parts, as above described, the shoes will be forced to expand by the cam by rotation of the wheel, due not only to the inertia of the shoes but also to the tendency of the band to be rotated by engagement with a work piece. Upon cessation of rotation of the wheel the spring 10 will contract the shoes to the po-

sition shown in Fig. 2 with the shoe plates engaging the outer face of the flanges 5 of the wheel rim.

Preferably the belt retaining rings 20 and 21 are provided with arcuate slots 34 which have an enlarged end 35 to permit placing the same over headed lugs 36 as shown in Fig. 1, or screws 37 as shown in Fig. 3. The ring may then be turned to bring the narrow portion of the slots beneath the headed pins or screws in a direction the reverse of the direction of rotation of the wheel so that the rings are maintained securely in place on the wheel when in use.

As previously stated the wheel may be utilized for various purposes in polishing or buffing various articles of various characters of material whether it be metal, wood or a plastic composition and the belt is provided with a polishing, abrading or buffing surface structure depending upon the kind of work to be performed. It may have a gritty or abrading surface or a wool or lint like fibrous material of either quite stiff or a quite fluffy soft surface but in either character of surfacing the belt must have a limited expansion or elasticity so that it will expand and contract with the outward or inward movement of the shoes and the frictional contact of the band with the shoe plates, when the shoes are in the expanded position, is mainly relied upon to prevent slippage of the band on the shoe plates. The rings 20 and 21 also may quite closely engage the side edges of the belt but not sufficient to prevent movement of the belt in a radial direction.

It is also pointed out that while the shoes 6 and the slotted rings 31 and 32 are loosely mounted in the channel 4 provided in the wheel rim, there is practically no movement of the shoes peripherally in relation to the wheel as the rollers 28 lie in a notch 28a at the low point of the cam 27 when the shoes are in the contracted position and the first effect produced by rotation of the wheel is due to the inertia of the shoes to cause the cam to turn beneath the pins and expand the shoes until the shoulders 23 of the shoes is in engagement with the inner face of the flanges 5 and the shoes are there held by the pressure of the cam on the pins. Upon cessation of rotation of the wheel the spring 10 causes the pins, to which the shoes are fixed, to ride downwardly to the low point of the cam and thus contract the shoes. The belt or band 16 of Fig. 3, or 19 of Fig. 6, are shown as having an outer work surfacing face parallel with the axis of rotation of the wheel. This face, however, may be varied in contour or otherwise formed as may be required for different shapes of work surface to be polished or buffed. The invention as hereinbefore described is not limited to an elastic or expandable circular work surfacing belt as the wheel may be used with a circular belt slightly greater in diameter than the diameter of the belt foundation when the shoes are in the contracted relationship, thereby permitting the belt to be readily assembled on the foundation. Under this relationship of parts the shoes carrying the curved plates forming the foundation for the belt will, upon expansion by means of the cams, be caused to move radially outward to increase the diameter of the belt foundation and thereby produce a sufficiently tight frictional contact of the belt with the foundation to prevent slippage of the belt when under rotation in contact with the work. This frictional contact between the belt and its foundation tends to cause the shoes to turn in a direction opposite the direction of rotation of the

wheel and thus to ride out on the relatively rotatable cams and thus increase the radial distance of the shoes from the wheel center as permitted by the belt or as limited by the shoulders 23 thereon and flanges 5 of the wheel rim.

It is believed evident from the foregoing description that our improved polishing and buffing wheel is of simple and comparatively inexpensive construction and automatically expandible and contractible and is of such construction that the more pressure applied to the work by the belt when the wheel is in use the greater the pressure applied to expand the shoes and maintain contact of the polishing and buffing surface of the belt with the work.

It is also pointed out that various changes and modifications may be made in the structure and arrangement of parts without departing from the spirit and scope of the invention as set forth in the appended claims.

Having thus briefly described our invention, what we claim and desire to secure by Letters Patent of the United States is—

1. A polishing and buffing wheel comprising a body portion attachable at its center to a shaft for rotation, an endless and diametrically expandible belt, having an outer face adapted for surface finishing of an article, means carried by the wheel providing a continuous, circular, non-yielding, foundation for the belt, means responding to the joint rotary urge of the shaft and the frictional retarding contact of the belt with the work for increasing the diameter of the foundation, and means limiting the extent to which the foundation may be increased in diameter.

2. A wheel for the purpose described, comprising a body having a rim and adapted for attachment at its center to a shaft for rotation of the same, a belt supported at the periphery of the wheel and having an outer face adapted for the surface finishing of an article, and means actuated by the frictional resistance of the belt to the rotation for causing the belt to be expanded while being rotated in contact with the piece of work to be finished, and means for causing the expanding means to contract upon cessation of rotation.

3. A wheel for the purpose described comprising a body having a rim and adapted for attachment at its center to a rotatable shaft for rotation of the same, an expandible endless belt having an outer face adapted for the surface finishing of an article, a belt supporting means at the periphery of the wheel, means functioning in response to the joint rotary urge of the shaft and the frictional retarding contact of the belt with the work to cause the belt supporting means to be increased in diameter and thus expand the belt, and means for automatically contracting the supporting means upon cessation of rotation of the wheel and thus effect contraction of the belt.

4. A wheel for the purpose described, comprising a body having a rim provided with a peripheral channel opening through the periphery of the rim, a belt supporting means in the said channel comprising a series of radially movable shoes together having an outer face forming a substantially continuous foundation for the belt, a belt having a semi-elastic base of a diameter to fit over the foundation provided by the shoes when in the radially inward position, a spring means for causing the shoes to move inwardly, and means for causing the shoes to move radially outwardly by rotation of the wheel with respect to the shoes.

5. A wheel for the purpose described, compris-

ing a body having a rim provided with a peripheral channel opening through the periphery of the rim, an endless, expandible, work surfacing belt, a belt supporting means in the channel comprising a series of radially movable shoes together having an outer surface forming a substantially continuous foundation for the belt, means for maintaining the shoes in equi-spaced relation in any position, means for causing the shoes to move inwardly to contracted position, and means whereby rotation of the wheel moves the shoe radially outward under restraint of the said shoe contracting means.

6. A wheel for the purpose described, comprising a body having a rim provided with a peripheral channel opening through the periphery of the rim, an endless, expandible, work surfacing belt, a belt supporting means in the channel comprising a series of radially movable shoes together having an outer surface forming a substantially continuous foundation for the belt, means for maintaining the shoes in equi-spaced relation in any position, means for causing the shoes to move inwardly to contracted position, means whereby rotation of the wheel moves the shoe radially outward under restraint of the said shoe contracting means, and means limiting outward movement of the shoes.

7. A wheel for the purpose described comprising a body having a circular rim provided with a peripheral channel opening through the periphery of the rim, a series of shoes loosely positioned in the channel, means for supporting the shoes in an equi-spaced relation in the channel, said means permitting a radial movement of the shoes, a work surfacing belt expandible in character and of endless form mounted on the shoes as a foundation, a series of cams carried by the wheel one for each shoe, each cam being formed on a curve eccentric to the axis of revolution of the wheel, a rotatable shaft secured to the center of the wheel, rotation of the shaft and wheel causing the cams to turn beneath the respective shoes to cause a radial movement thereof and thus expand the belt diameter to maintain the work contacting surface thereof in engagement with the work, means acting upon cessation of rotation of the wheel to cause the shoes to ride diametrically inwardly to the low point of the respective cams, and means carried by the rim for preventing lateral displacement of the belt on the shoes.

8. A wheel for the purpose described, comprising a body having a circular rim provided with a peripheral channel opening through the periphery of the rim, a series of shoes loosely positioned in the channel, means for supporting the shoes in an equi-spaced relation in the channel, said means permitting a radial movement of the shoes, a work surfacing belt expandible in character and of endless form mounted on the shoes as a foundation, a series of cams carried by the wheel one for each shoe, each cam being formed on a curve eccentric to the axis of revolution of the wheel, a rotatable shaft secured to the center of the wheel, rotation of the shaft and wheel causing the cams to turn beneath the respective shoes to cause a radial movement thereof and thus expand the belt diameter to maintain the work contacting surface thereof in engagement with the work, means acting upon cessation of rotation of the wheel to cause the shoes to ride diametrically inwardly to the low point of the respective cams, means on the rim at opposite sides of the channel opening limiting outward movement of the shoes by the cams, and means carried by the rim for

preventing lateral displacement of the belt on the shoes.

9. A wheel for the purpose described, comprising a body having a circular rim provided with a peripheral channel opening through the periphery of the rim, a series of shoes loosely positioned in the channel, means for supporting the shoes in an equi-spaced relation in the channel, said means permitting a radial movement of the shoes, a work surfacing belt expandible in character and of endless form mounted on the shoes as a foundation, a series of cams carried by the wheel one for each shoe, each cam being formed on a curve eccentric to the axis of revolution of the wheel, a rotatable shaft secured to the center of the wheel, rotation of the shaft and wheel causing the cams to turn beneath the respective shoes to cause a radial movement thereof and thus expand the belt diameter to maintain the work contacting surface thereof in engagement with the work, an endless coiled spring carried by the shoes tending to move the shoes radially inward to the low point of the respective cams to thereby contract the belt foundation, and means for preventing lateral displacement of the belt on the shoes.

10. A wheel for the purpose described, comprising a body having a rim and adapted for attachment at its center to a rotatable shaft for rotation of the same, an expandible, work surfacing belt of circular form carried at the periphery of the wheel, and means responsive to the braking effect applied to the belt by rotation of the wheel with the belt in contact with the surface to be finished to automatically cause an increase in the diameter of the belt and means causing a decrease in belt diameter on cessation of rotation of the wheel.

11. A wheel for the purpose described comprising a body having a circular rim and a central hub adapted for attachment to a rotatable shaft, a diametrically expandible belt supporting means carried at the wheel rim in a relatively rotatable relation, a work surfacing belt of circular form carried by the belt supporting means, means whereby the belt supporting means is caused to increase in diameter by rotation of the wheel to thereby cause tight frictional contact between the belt and its supporting means, the whole providing a structure whereby the pressure applied to the belt in a work surfacing operation tends to rotate the expandible belt supporting means in a direction opposite the direction of rotation of the wheel thereby tending to further increase the diameter of the belt supporting means.

12. A wheel for the purpose described comprising a body having a circular rim and a central hub attachable to a rotatable shaft, a diametrically expandible belt supporting means of circular form carried at the wheel rim in a relatively rotatable relation, a work surfacing belt of circular form carried by the belt supporting means, the diameter of the belt being slightly greater than the diameter of the belt supporting means when in normal contracted position to permit assembly of the belt on the belt supporting means, and means whereby the said belt supporting means is caused to increase in diameter by rotation of the wheel in contact with the work to thereby cause a tight frictional engagement between the belt and its said supporting means, and means for causing a decrease in diameter of the belt supporting means upon cessation of rotation.

13. A wheel for the purpose described comprising a body having a circular rim provided with a peripheral recess opening through the rim, a rela-

tively rotatable and diametrically expandible belt supporting means in said wheel recess comprising a series of like shoes each having a belt contacting plate, the said plates each being formed on a radius and adapted to inter-engage with the ends of the plates of adjacent shoes to form a circular belt foundation, a circular belt having a work engaging outer surface and normally loosely fitting on the foundation, means for causing the said shoes to be moved radially outward to provide tight engagement between the shoe plates and the belt by rotation of the wheel with the belt in contact with a work surface to thereby prevent rotation of the belt on the shoe plates, and means for automatically causing the shoes to move radially inward upon the cessation of rotation of the wheel.

14. A wheel for the purpose described, comprising a body having a circular rim and a central hub attachable to a rotatable shaft, a relatively rotatable and a diametrically expandible belt supporting means at the wheel rim, a work surfacing belt of circular form carried by the belt supporting means, the diameter of the belt being slightly greater than the diameter of the belt supporting means when in contracted position to permit the belt to be assembled thereon, means associated with the wheel rim for preventing material lateral displacement of the belt relative to its supporting means, means carried by the wheel and cooperative means carried by the belt supporting means whereby rotation of the wheel with the belt in pressure contact with the work surface automatically causes an increase in the diameter of the belt supporting means to thereby engage the inner face of the belt under sufficient pressure to prevent material rotative displacement of the belt relative to its supporting means in a work surfacing operation.

15. A wheel for the purpose described, comprising a body having a circular rim and a central hub attachable to a rotatable shaft, a relatively rotatable and a diametrically expandible belt supporting means at the wheel rim, a work surfacing belt of circular form carried by the belt supporting means, the diameter of the belt being slightly greater than the diameter of the belt supporting means when in contracted position to permit the belt to be assembled thereon, means carried by the wheel and cooperative means carried by the belt supporting means whereby rotation of the wheel with the belt in pressure contact with the work surface automatically causes an increase in the diameter of the belt supporting means to thereby engage the inner face of the belt under sufficient pressure to prevent material rotative displacement of the belt relative to its supporting means in a work surfacing operation.

16. A wheel for the purpose described comprising a body having a rim provided with a circumferential channel and adapted for attachment at its center to a rotatable shaft for rotation of the same, a radially expandible and contractible belt foundation carried in the rim channel, a work surfacing belt of circular form mounted on the belt foundation, and means on the wheel and means on the belt foundation cooperatively responsive to the braking effect applied to the belt by rotation thereof in contact with the work to automatically cause an increase in the diameter of the belt foundation to tight engagement with the belt and thereby prevent rotation of the belt in respect to the belt foundation while in pressure contact with the work during a work finishing operation.

17. The combination with a wheel having pre-determined minimum and maximum diameters of expanding peripheral surface of circular form, of an endless belt of circular form positioned on said peripheral surface of the wheel, said belt having a minimum diameter greater than the minimum diameter of said expandible surface, and a maximum diameter less than the maximum diameter of said expandible surface, means functioning in

5 response to the joint rotary urge of the shaft and frictional retarding contact of the belt with the work for causing an expansion of the wheel, and means for automatically contracting the wheel on cessation of frictional retarding contact of the belt with the work.
